(57) **CLAIM**

The ornamental design for a fan-shaped bookshelf with a lamp, as shown and described.

DESCRIPTION

FIG. 1 is a front, right perspective view of a first embodiment of a fan-shaped bookshelf with a lamp showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a top perspective view thereof;

FIG. 9 is a front, right perspective view of a second embodiment of the fan-shaped bookshelf with a lamp;

FIG. 10 is a front view thereof;

FIG. 11 is a rear view thereof;

FIG. 12 is a right side view thereof;

FIG. 13 is a left side view thereof;

FIG. 14 is a top view thereof;

FIG. 15 is a bottom view thereof; and,

FIG. 16 is a top perspective view thereof.

1 Claim, 14 Drawing Sheets
